(No Model.)

H. L. SELLE.
WASHING MACHINE.

No. 599,262.

Patented Feb. 15, 1898.

UNITED STATES PATENT OFFICE.

HENRY L. SELLE, OF IVESDALE, ILLINOIS.

WASHING-MACHINE.

SPECIFICATION forming part of Letters Patent No. 599,262, dated February 15, 1898.

Application filed March 25, 1897. Serial No. 629,110. (No model.)

To all whom it may concern:

Be it known that I, HENRY L. SELLE, of Ivesdale, in the county of Champaign and State of Illinois, have invented certain new and useful 5 Improvements in Washing-Machines; and I do hereby declare the following to be a full, clear, and exact description of the invention, such as will enable others skilled in the art to which it appertains to make and use the same.

10 This invention relates to improvements in washing-machines, and has more particular relation to washing-machines of the reciprocating-rubber type.

The invention consists of certain novel constructions, combinations, and arrangements of parts, all of which will be hereinafter more particularly set forth and claimed.

In the accompanying drawings, forming part of this specification, Figure 1 represents 20 a side elevation of the apparatus embodying my invention, the inoperative positions of the respective parts of the same being shown in dotted lines. Fig. 2 represents a central vertical longitudinal section through the same. 25 Fig. 3 represents an enlarged detail perspective view of one of the pendent guides, and Fig. 4 represents an enlarged detail perspective view of the slotted spider.

1 in the drawings represents the containing-casing; 2, the cover of the same; 3 the auxiliary movable bottom; 4, the rubber, and 5 the operating-lever. The casing 1 may be made of any desired material and has its respective sides and bottom secured together 35 by means of iron strips 6, so as to form water-tight joints. Said casing is supported in position by a plurality of supporting-legs 7, of any desired construction, and suitably bolted or screwed thereto. The cover 2 of 40 said casing is hinged thereto at 8, so that it may be turned up or down at will to permit of the placing of the articles to be washed within the casing 1. The auxiliary bottom 3 comprises a main frame 9, provided upon its 45 upper surface with a plurality of lateral bars 10, preferably triangular in cross-section and placed with their edges together, so as to form a contiguous serrated surface over which the clothes are rubbed. The frame 9 is supported 50 in position in the casing 1 by guides or sup-

ports 9^a, secured to the sides of said casing. The said frame 9 is of a width equal to the width of the casing 1, but is sufficiently shorter than the same to permit of its reciprocation therein.

55

In order to prevent the clothes or other articles being washed from passing under the respective ends of the frame 9 during its reciprocations, I provide each end of said frame with a hinged wing 11, having serrated surfaces and adapted to normally lie against the ends of the casing 1. By this peculiar construction the auxiliary bottom extends entirely across the bottom of the casing 1, but at the same time is permitted to be reciprocated by the hinged connection between the frame 9 and the wings 11. In order to cause the reciprocation of said auxiliary bottom, I provide the same with a longitudinal plate 12, rigidly secured thereto and projecting at one 60 end to form an apertured ear 13, to which is secured a rod 14. This rod passes through a packing 15, mounted in the end of the casing 1, and is guided in its reciprocations by an angular apertured bracket 16, secured to the 65 under side of the casing 1. Said packing 15 comprises a headed sleeve 17, which surrounds the rod 14, a rubber disk 18, mounted on said sleeve, and a tightening-nut 19, adapted to be screwed on the end of said sleeve and 70 force the rubber washer 18 firmly against the end of the casing 1 and the rod 14, and thus form a water-tight joint at this point. The said rod 14 is formed near its outer end with screw-threads 20, adapted to be engaged 75 by clamping-nuts 21, between which is secured an angular apertured bracket 22, which is first slipped over the end of said rod 14. The outer end of said bracket 22 is provided with a laterally-projecting pin 23, which is 80 mounted in an elongated slot 24, formed in the lower end of the operating-lever 5. This lever 5 is provided upon each side with a laterally-extending trunnion 25, said trunnions being seated, respectively, in spaced hooks 85 or trunnion-supports 26, secured to the end of the casing 1. The upper operative end of said lever 5 is connected to a crank-shaft 27 by a pitman 28. This shaft 27 is journaled 90 in vertical standards or brackets 29, secured 95 100

to the upper surface of the cover 2, so that said crank-shaft is raised or lowered with said cover. The outer end of said crank-shaft is provided with a balanced wheel 30, 5 whereby the desired regularity of movement is secured. An angular spider 31 is secured to the upper surface of the cover 2 and is formed with an elongated slot 32, which lies directly over a similar elongated slot 33, 10 formed in the said cover 2. Pendent slotted guides 34 are mounted upon the under side of said cover 2 upon each side of the slot 33 and are adapted to receive trunnions 35, mounted upon the respective sides of the lever 36, the upper end of which is connected 15 to the crank-shaft 27 by means of a pivoted link 37. A coil-spring 38 surrounds the said lever 36 and bears with its upper end against the spider 31 and its lower end against the trunnions 35. It will be observed from the 20 foregoing that the lever 36 is normally held down with its trunnions 35 in the lower ends of the slotted pendent guides 34 under spring tension, so that they may rise under pressure. The scrubber or rubber 4, which is 25 formed with a corrugated under surface, is pivotally mounted upon the lower end of said lever 36, so as to be reciprocated back and forth by the oscillations of said lever upon its trunnions. A suitable operating-handle 30 is mounted upon one end of the crank-shaft 27, whereby the machine may be operated by hand or any other suitable power. Said casing 1 is preferably provided with a draw-off cock 39, whereby the contents of the casing 35 may be removed when so desired.

It will be observed from the foregoing description that when it is desired to place the articles that are to be washed within the casing 1 the cover 2 is raised and the trunnions 25 of the operating-lever 5 will move away from their respective hooks. This action removes the scrubber and its operating mechanism to one side, so that the upper end of 45 the casing remains open and free. After the articles have been inserted the cover is again closed and the trunnions 25 placed in the hooks 26, the lever 36 rising according to the amount of articles beneath the same under 50 the tension of the spring 38. The crank-shaft 27 is now rotated, which causes the lever 4 to move in one direction and the auxiliary bottom 3 to move in an opposite direction and thoroughly scrub the articles between the same. The said rubber 4 is always held in intimate contact with the clothes or other articles being washed to force them 55 against the auxiliary bottom 3 by the coil-spring 38, which surrounds the lever 36 and 60 normally forces the same downward.

The operation of my improved washing-machine is quick and effective and the peculiar arrangement of the pivoted cover carrying the operating mechanism greatly expedites the loading and unloading of the casing.

Having thus described the invention, what is claimed as new, and desired to be secured by Letters Patent, is—

1. In a washing-machine, the combination 70 with a suitable casing of an auxiliary movable bottom, hinged wings connected to the opposite ends of the same and adapted to rest against the ends of the casing, a movable rubber mounted above said bottom, and 75 means connecting said rubber and bottom, whereby they are operated simultaneously to scrub the articles placed between them.

2. In a washing-machine, the combination 80 with a suitable casing, of an auxiliary movable bottom mounted therein, a rod connected with said bottom and extending from said casing, a pivoted lever mounted on said casing and connected to said rod, a hinged cover for said casing, a pivoted lever mounted on 85 said cover and connected to the first-mentioned lever, and a rubber mounted on the lower end of the lever carried by the cover and adapted to scrub the articles placed between it and the auxiliary movable bottom, 90 substantially as described.

3. In a washing-machine, the combination 95 with a suitable casing, of an auxiliary bottom movably mounted therein, a rod connected to said bottom and extending from said casing, a lever pivotally mounted upon said casing and connected to said rod, a hinged cover for said casing, a crank-shaft mounted on said cover, means connecting the crank-shaft and said lever, another lever pivotally mounted 100 on said cover and connected to said crank-shaft, and a rubber mounted upon the lower end of said latter lever, substantially as described.

4. In a washing-machine, the combination 105 with a suitable casing, of an auxiliary movable bottom mounted therein, a rod connected to said bottom and extending from said casing, a pivoted lever mounted on said casing and connected to said rod, a hinged cover for 110 said casing, a crank-shaft mounted on said cover and connected to said lever, another lever pivotally mounted on said casing and connected to said crank-shaft, a spring surrounding said latter lever to normally force it downward by engaging a portion of the casing and a suitable projection mounted on said lever, and a rubber mounted upon the lower end of 115 said latter lever, substantially as described.

5. In a washing-machine, the combination 120 with a suitable casing of the movable bottom, a lever connected therewith for reciprocating the same, a second lever having a movable fulcrum in vertical guides above the movable bottom, a rubber connected with said second 125 lever to coöperate with the movable bottom, and a crank-shaft having pitman connection with both of said levers for operating the same, as shown and described.

6. In a washing-machine, the combination 130 with a suitable casing of the movable bottom, a lever for reciprocating the same, a second

lever having a movable fulcrum in vertical guides above the movable bottom, a rubber connected with said second lever to coöperate with the movable bottom, a spring arranged and operating to press said rubber toward the bottom, and a crank-shaft having oppositely-extending cranks connected with said levers, respectively, as shown and described.

In testimony whereof I have signed this specification in the presence of two subscribing witnesses.

HENRY L. SELLE.
